Attorney.

UNITED STATES PATENT OFFICE

CHARLES EDWARD BARRETT, OF YONKERS, NEW YORK, ASSIGNOR TO ALEXANDER SMITH & SONS CARPET COMPANY, OF YONKERS, NEW YORK, A CORPORATION OF NEW YORK

INDICATOR FOR CARPET LOOMS

Application filed September 29, 1930. Serial No. 484,990.

In the weaving of carpets having a repeat pattern it is necessary that the pattern blocks be each comprised as near as may be in the same number of shuttle threads or cross rows of tufts and within the same lengths of carpet, and this, not only as to different parts of the carpet woven on the same loom, but also as to carpets woven on different looms and running on the same pattern, so that when successive breadths are placed side by side there will be a proper matching of the pattern between them. To maintain the pattern blocks of proper length requires especial watchfulness on the part of the attendant in the case of looms wherein the carpet is woven with a ground of warp and weft threads and a pattern surface formed by pile threads which carry the pattern and are fed from a separate pile beam from the warp beams from which the warp threads are fed for the ground.

Should the tension on the pile threads be too great they will be drawn too tightly over the pile wires and a pattern block will run over more than the intended number of cross rows, and if the tension is too light a pattern block will be taken up in less than the intended number of cross rows. As the threads are drawn from the pile beam and its diameter to the top of the threads changes it becomes necessary to make adjustments to maintain the proper tension at the weaving point. It is therefore to be expected that a pattern block will not be comprised accurately in the intended number of cross rows, and, while the pattern block may readily keep closely enough to the intended number of cross rows so that the error will escape general observation, yet the error will be apparent to the attendant if means are provided to inform her each time that the number of rows have been woven in which the pattern block is to be comprised.

In case that a pattern block has run over and is too long, the tension on the pile threads is reduced so that the next pattern block will run short, and in case that a pattern block has run short the tension is increased so that the next pattern block will run over. In this way the error will be kept from becom-

ing cumulative and means to assist the attendant in noting any departure is one of the objects of this invention.

It is also important for the proper matching of breadths that a given number of cross rows be comprised within the same length of carpet, for variation in this regard may also result from altered tension and particularly from variations in the size of the pile threads. This variation may also arise in weaving on Jacquard looms. A further object is to provide means to assist the attendant in preserving the weave uniform in this respect.

This means consists in an indicator suitably located where it can be conveniently watched by the attendant while she is also watching the operation of the loom and the forming of the pattern, such indicator being suitably geared to mark the weaving of the number of rows in which the pattern block is to be comprised.

In the accompanying sheet of drawings which forms a part of this description,

Figure 1 is a diagrammatic side elevation of a pile wire loom inside the frame with an indicator which embodies this invention.

Fig. 2 is an enlarged plan view of the breast beam, pile wires and indicator.

Fig. 3 is an elevation of the same.

In the loom, warp beams 6, 6 supply the warp threads 7, 7 for the ground weave, and a pile beam 8 supplies the threads or yarns 9, 9 for the pile or tufts on which the pattern appears.

As the carpet is woven, pile wires 10, 10 are inserted and the pile threads are looped over them. These pile wires project beyond the margin of the carpet and usually have cutters 11, 11 formed at their ends to cut the loops and form tufts as the wires are withdrawn. The pile wires remain in the woven carpet for a distance as it passes over the top flange or plate 12 of the breast beam 13. A number of the pile wires lie in a row side by side in the carpet spaced by the pile threads 95 looped over them. A wire is withdrawn at one end of the row and is inserted at the other end of the row where the weaving is taking place at each operation of the loom, and the intermediate wires travel for a short dis-

tance with the carpet. The carpet passes after the wires have been withdrawn to a draw-off roll 14.

An indicator bracket 15 is bolted to the underside of the breast-beam plate. This supports a toothed wheel 16 through a shaft 17. The toothed wheel projects through a slot in the breast beam plate and is engaged by the row of pile wires where they project beyond the edge of the carpet. These wires act as rack teeth to drive the toothed wheel. On the shaft with the toothed wheel is a worm 18 which engages a worm wheel 19 on a vertical shaft 20, and the vertical shaft carries an indicator 21. The indicator is at the edge of the breast-beam plate close by where the weaving is taking place so that both can be conveniently watched together by the attendant.

The number of teeth in the toothed wheel multiplied by the ratio of the worm and worm wheel equals the number of pile loops or tuft rows that are to comprise each pattern block, and at each revolution of the indicator the attendant watches for the completion of a pattern block and the commencement of the next pattern block at the weaving point and notes by the indicator how much it has overrun or fallen short and alters the tensions as required to prevent any error from accumulating. There is a main indicator point and graduations on either side by which the amount of error can be read, and the amount of required change in adjustment estimated.

Also the pattern block and the number of rows in which it should be comprised may be measured and if any departure from standard is found correction is made in the force with which the weave is rammed.

I claim:

1. The combination with a carpet loom, of pile wires carried by the woven carpet, a toothed wheel in engagement with the projecting ends of the pile wires, and an indicator supported from the framework of the loom and driven from the toothed wheel.
2. The combination with a carpet loom having a breast-beam plate, of pile wires carried by the woven carpet, an indicator bracket attached to the breast-beam plate, an indicator mounted thereon, and a toothed wheel in engagement with the projecting ends of the pile wires and connected with the indicator for the operation thereof.

CHARLES E. BARRETT.
